UNITED STATES PATENT OFFICE.

DAVID J. POWERS, OF CHICAGO, ILLINOIS, ASSIGNOR TO THE UNION WIRE MATTRESS COMPANY, OF SAME PLACE.

FOLDING BED.

SPECIFICATION forming part of Letters Patent No. 321,911, dated July 7, 1885.

Application filed May 11, 1883. (No model.)

To all whom it may concern:

Be it known that I, DAVID J. POWERS, a citizen of the United States, residing at Chicago, in the county of Cook and State of Illinois, have invented new and useful Improvements in Folding Beds, of which the following is a specification.

My invention relates to improvements in folding beds; and it consists, first, in a device for stretching transversely and supporting the elastic fabric bed-bottom; secondly, in attaching the elastic bottom to a limited extent to the side rails to counteract lateral contraction; thirdly, in a certain detachable hinge device for connecting the rail structure and head and foot sections of the case; and, fourthly, in a certain opening in the base of the case, when closed, for ventilation.

Figure 1 of the drawings shows the bed closed; Fig. 2, a sectional view of Fig. 1, partly open; Fig. 3, fully open; Fig. 4, a cross-section on line $\alpha\alpha$ of Fig. 3; Fig. 5, a longitudinal central section of portions of the side rails and stretching device; Fig. 6, a plan view of the bottom of the case, showing the arrangement of the casters, blocks, and rollers and their supports, also the ventilating opening; Fig. 7 shows a sectional view of the detachable hinge device; Fig. 8, a plan view of the same; Fig. 9, the portion of the hinge with the lug, and Fig. 10 the slotted portion; and Fig. 11, a plan view of a portion of the bed-bottom, showing the side attachment of the fabric to the frame.

35 The same letters represent the parts both in the drawings and specification.

My improvements are adapted, principally, to such a folding bed as is set forth in my Letters Patent granted April 24, 1883, and numbered 276,464; and as in said patent the head end of my present case is lettered A, the foot end B, the side rails C, pivoted at $\alpha\alpha$ to the head and foot sections and hinged at their middle. To the side rails, at their outer ends, 45 are secured end rails, D D, to which are attached the opposite ends of an elastic metallic fabric of woven-wire coils, G, or of other equivalent character, and of the proper length to be sufficiently tight for use when the side 50 rails are extended. A center cross-rail, D', is secured to pendants from the side rails; and

to the opposite ends of rail D' are pivoted the straining-braces d d at their straight end, and the opposite upward-curving ends are secured to the margin of the fabric at E E, and being attached to the fabric above their plane of attachment to the bar D' they necessarily stretch or spread the fabric when borne down by an occupant of the bed, and thus strengthen and support it and counteract its tendency to settle or sag in the center, or to contract or narrow centrally, when the bed is folded and the fabric slackened endwise.

The device is equally applicable to a woven-wire mattress upon an ordinary frame, so far as supporting the same to prevent it from sagging is concerned, and may be applied directly to the side rails of a mattress or folding bed, or upon pendants, as shown in Fig. 3 of the drawings; and one or more sets of 7c the braces may be applied at different points upon or beneath the side rails, as found desirable, a pendant, f, being shown in Fig. 3 for this purpose. Fig. 4 shows substantially the manner of applying these braces, and the 75 dotted lines show the expanding effect of the device when borne down.

When a bed is folded with a woven-wire fabric, the fabric is inclined to spring in toward the center. To counteract this tendency, 80 when the stretching-braces above described are not used the attaching of the fabric for a short distance from its ends, as shown in Fig. 11, is a cheap mode of counteracting this 85 tendency.

I do not claim to be the first to attach a fabric at its sides, generally, but only in a folding bed to counteract the difficulty stated. The front section of the bed-case has base-runners h underneath and extending inward, 90 as shown in Figs. 2 and 3, upon the under side of which are casters i i. The head-section of the case also has similar runners, with casters at their inner ends, and blocks of wood j at their rear ends, instead of casters. These 95 blocks are not as thick as the casters are high, so that the head-section of the case, when supported upon its casters and blocks, pitches back a little, as shown by dotted lines in Fig. 1. The same is also true of the foot-section, 100 the front casters being a little shorter than the back ones, causing it to pitch a little for-

ward; and when the two sections are closed together and secured thus the caster *i* is at the back of the inclosed case, and *i'* is at the front; and the bringing the case-inclosing up to a vertical lift-block, *j*, and caster *i* off from the floor, and leaves the entire case mounted upon the four casters at the inner ends of the runners, so that it can readily be moved when closed, and so that when the sections are unlocked and fall back to the dotted lines before mentioned the head-section becomes anchored to the floor, so that it will not follow the foot end when being drawn out in the process of opening—a very essential result in a folding bed with a foot-section adapted to be drawn back and forth.

The detachable hinges consist of plates *n*, with a stud projecting from one side of them adapted to be secured to the inside of the head and foot sections of the case at *a a* with the studs projecting inward for about half an inch. To the outside of the side rails, at a proper distance from their ends, are attached the angular slotted plates *o* in the position shown in Fig. 3, (also see plates *n* and *o*, shown by Figs. 9 and 10.) The slats preserve their diagonal position both when the bed is folded and unfolded, thus preventing their becoming detached; but when the bed is unfolded the rail-section can readily be lifted out or replaced without the use of tools, thus often proving a convenience in handling and removing to clean; or otherwise these plates may be varied in form more or less, as found desirable.

The inner sides of the bottom are cut out, as shown in Fig. 6, for the purposes of ventilation and lightness, such bottom ventilation being found much more efficient than openings higher up and only upon the back, for the reason that air entering centrally at the bottom circulates upward equally upon both sides of the folded bedding.

Having thus described my improvements, what I consider new, and desire to secure by Letters Patent, are as follows:

1. In a bed-bottom, a supporting-frame, in

combination with a continuous elastic fabric attached at its respective ends to the supporting-frame, but with its side edges free 55 their whole length, or nearly so, and supports connected to said free edges to hold them out when moving down under pressure, substantially as described.

2. In a bed-bottom, a supporting-frame, in 55 combination with a continuous elastic fabric attached at its ends to said frame, but with its side edges free, and yielding spreading supports connected to said free edges, substantially as and for the purposes set forth.

3. In a bed-bottom, suitable end supports for the bottom fabric, in combination with a continuous elastic fabric attached at its respective ends to said supports, but having its side edges free the whole length, or nearly so, 65 of the bed, and cross braces or levers pivoted at one end to a support below the fabric, and at their opposite ends connected to the opposite side edges of said fabric, but otherwise free to vibrate on their pivots, substantially 70 as and for the purposes set forth.

4. In a folding bed, suitable supports for the bottom fabric, in combination with a continuous elastic fabric attached at its respective ends to said supports, folding side rails, a 75 cross-bar attached to said rails and arranged underneath the elastic fabric, and cross-braces or levers pivoted at one end to the cross-bar and connected at their other ends to the opposite side edges of the fabric, but otherwise 80 free to vibrate on their pivots, substantially as and for the purposes set forth.

5. In a bed-bottom, suitable end supports for the bottom fabric, in combination with a continuous elastic fabric attached at its respective ends to said supports, and side rails 85 to which the fabric is connected at each edge for a short distance from each end support, substantially as and for the purposes set forth.

DAVID J. POWERS.
